Application August 21, 1936, Serial No. 97,104

18 Claims.

(Cl. 93—18)

My invention pertains in general to packaging equipment and specifically relates to a form of combined automatic and manually operated package enclosure forming mechanism.

5 The principal object of my invention is to provide a machine organization for the fabrication of envelope enclosure structures suitable for packaging commodity articles and preferably, but not exclusively, composed of regenerated cellulose materials.

10 A further object consists in providing a machine with adjustable parts that will permit the fabrication of package enclosures of varying dimensions of width and length.

15 Another object is to provide a correlated combination of automatic and manually operating units, each independent of the other in its specific operation but cooperating to provide the rapid and continuous production of package enclosures.

20 A further object is to provide a machine for producing package enclosures and having means for incorporating insert strips in the edges of the package structure to effect a reenforcement 25 of the edges of the enclosure and also to give an ornamental and more attractive appearance to the package.

25 These and other objects reside in a construction of a package enclosure forming machine and a method of manufacture as will be readily apparent from the following description in conjunction with the appended drawings in which like reference numerals designate corresponding parts and in which:—

30 Fig. 1 is a side view, partially sectioned, of the central portion of one embodiment of an enclosure forming machine according to this invention;

35 Fig. 2 is a front elevation, partially sectioned, of the composite heating, pressing, crimping, and severing equipment employed in the invention;

40 Fig. 3 is a top plan view of a portion of the representation of Fig. 2;

45 Fig. 4 is a fragmentary top plan view, partly in section, taken along line 4—4 of Fig. 2;

50 Fig. 5 is a vertical sectional view taken along the line 5—5 of Fig. 1, illustrating the composite heating and crimping equipment as well as the method of incorporating and combining the insert strips with other packaging materials;

55 Fig. 6 is a vertical sectional view taken along the line 6—6 of the representation of Fig. 2;

Fig. 7 is a perspective view of a package structure produced by the machine of this invention; and

Fig. 8 is a plan view of an individual package enclosure severed along the line Y—Y of Fig. 7.

This invention contemplates the production of packaging enclosures of envelope formation. These enclosures are of a continuous, flat, tube-like structure preferably composed of various superimposed layers of transparent regenerated cellulose material having a heat treatment coating thereon. In accordance with one aspect of the invention, additional strips of colored cellulose material are incorporated in the marginal edges of the packaging enclosure.

In fabricating the package structure, the edges of superimposed layers of the packaging material are subjected to a pressure, heating and crimping process which bonds and seals the edges in a rapid and continuous automatic operation, producing an envelope package structure that is transparent, sanitary and moisture proof. The machine organization to produce this packaging 15 enclosure structure is designed with adjustable parts so that varying sizes of packages can be produced by minor adjustments. The mechanism is partly automatic and partly manually operated and is so designed that intermittent 20 operation of the manually operated part does not necessitate an interruption in the continuous 25 operation of the automatic part. The automatic part of the mechanism operates to produce a continuous supply of tubular package structure 30 while the manually controlled part of the mechanism operates to close this packaging structure at selected points by heating and crimping and, at the same time, severs the structure into predetermined lengths forming individual envelopes. 35

During the intermittent operation of the manually controlled mechanism to produce envelope structures of desired lengths, there will be an accumulated surplus of the flat tubular structure produced by the continuously operated automatic part of the mechanism. This accumulation from the continuously operated part of the mechanism is accommodated by an intermediate storing arrangement.

Referring to the drawings in detail and particularly to Fig. 1, there is provided a general mounting structure 12, having two reels 2 and 4 associated therewith and mounted on spindles carried by parts of the general mounting structure not shown. These reels are provided with central 50 cores upon which rolls of packaging material are respectively stowed for rotatable feeding purposes. The packaging material so provided is preferably of transparent strip or ribbon formation and is of a composition such as regenerated cellulose, 55

with a heat treatment coating thereon, although other material may be employed. Extending from the rolls of packaging material, mounted on reels 2 and 4, are leader strips 1 and 3, respectively. The bottom leader strip 1 is wider than the top strip 3, Fig. 5, so as to allow the excess margin to fold up over and around the edges of the narrower strip 3.

These leader strips 1 and 3 extend centrally of the mounting structure in directions toward each other and pass over loose sleeve idler rollers 9 and 14 mounted on shafts 10 and 15, Figs. 1 and 5, and thence feed into the heating and sealing equipment described in more detail later.

15 Also positioned on parts of the general mounting structure 12, are two reels 6 and 8, upon which are stowed rolls of narrow strips of colored packaging material. These reels are positioned so that the outside edges of leader insert strips 5 and 7, 20 Fig. 5, will travel under and in alignment with the outside edges of the bottom packaging strip 1 and over idler roller 14. Thus, when the extending marginal edges of the strip 1 are folded over the edges of strip 3, one half of the width of the 25 colored strips are at the same time folded over on top of the folded-over edges of the bottom strip 1. Thus the colored strips form a U-shaped binder for the outside edges of the combined strips 1 and 3. It will be understood that the 30 use of the insert strips 5 and 7 is optional, and that the enclosure structure may be fabricated with these strips omitted.

The folding-over process is effected when the edges of the strip and the colored insert strips 5 and 7 come in contact with pin members 18 and 22, Fig. 5, as the strips are fed from the reels to the crimping rollers. The pin members 18 and 22 are movably secured to shaft 19 which in turn is mounted in part of the general mounting structure 12. There is provided a corrugated roller 23, mounted in bearings in the general mounting structure, the purpose of which is to straighten the packaging material and prevent wrinkling and buckling of the same before feeding to the 45 crimping rollers. On this corrugated roller, there are provided two guide members 29 and 30, adjustably secured to the roller in position on either side of the edges of the packaging strips to properly guide the turned-over edges into the edge crimping rollers. These guide members are movable to provide for varying widths of packaging materials. There are also provided on the corrugated roller 23 two collar members 26 and 27, secured to the roller to maintain the same in a 50 fixed lateral position.

In Figs. 1 and 5 is illustrated the arrangement of the heating and crimping rollers through which the several combined packaging materials are passed whereby the marginal edges thereof are subjected to a heated pressure and crimping process to produce the tubular packaging structure. There are provided two sets of these crimping rollers 31 and 32, 33 and 34, the peripheral surfaces of which are serrated, these serrations being spaced in multiples relative to the pitch of spur gears 39-40 and so arranged that the indentations of the surfaces of the lower and upper rollers of each set mesh into each other to effect a crimping of the edges of the packaging material. 60 The two rollers 31 and 33 are adjustably secured to the shaft 38, and laterally positioned to contact the turned-over edges of the packaging strips. The rollers 32 and 34, are secured to shaft 35 in a similar manner.

70 The roller shafts 35 and 38 are hollow to allow

for heating cartridges 41 and 43, Fig. 1, which supply heat to the rollers. These heating cartridges are provided with electric terminals 42 and 46, Fig. 5, to provide current for heating purposes.

The crimping rollers are rotated through the gear 39 on shaft 38, Figs. 1 and 5, which meshes with gear 40 keyed on shaft 35. These gears are rotatably driven by a gear 48 keyed to the end of shaft 38, Fig. 1, which gear in turn is driven by 10 driving gear 50, Fig. 1, through the intermediate gear 49, driving gear 50 being keyed to shaft 51 aligned with the driving shaft of a motor, 56, Fig. 5. Clutch members 52 are provided to selectively connect and disconnect the motor from the train 15 of driving gears. The driving clutch member is controlled by pin member 54 mounted on pivoted member 53, Fig. 5, and operable by a hand lever member 55.

To allow for the movement of the set of crimping rollers 32 and 34, so as to thread and make adjustments of the packaging strips with respect to the rollers, there is provided a pair of movable blocks 60 which carry the crimping roller shaft 35, Fig. 1. These frame blocks rotate on pivots 25 61 secured to bosses 62 at opposite sides of the frame 12. The frame blocks 60 are provided with extension members 63 which may be actuated by an eccentric roller member 64 mounted in suitable bearings in the frame 12. This eccentric roller 30 when rotated by the hand lever 68, Fig. 5, depresses the extension members 63 thereby causing the crimping rollers 32 and 34 to disengage from the lower rollers allowing for threading and adjustment of the packaging strips between the 35 rollers. After this threading or adjustment is completed, the hand lever 58 can be operated to rotate the eccentric roller 64 back to its normal position whereby the movable set of crimping rollers are forced into engagement with the other 40 rollers through the action of springs 66, Fig. 1. To regulate the force exerted by the upper rollers on the packaging strip, there is provided a set screw 67 for adjusting spring 66.

As shown in Figs. 1 and 5, there is provided a, 45 floating, or tensioning sleeve roller 70 loosely fitted on a shaft 71. Pinion gears 72 are keyed to the ends of shaft 71. These gears mesh into upright toothed rack members 73 and 87. The extended ends of the shaft 71 rotate in contact 50 with upright guide members 74 and 88. The purpose of this floating roller 70 is to take up the slack of the packaging material moving continuously from the crimping rollers. This slack accumulates when the hand operated mechanism is 55 operated to seal a portion of the package structure.

The roller 70 operates in a vertical plane, and is prevented from tilting or slipping from its horizontal position by the two end gears meshing with the toothed rack members 73 and 87. The engagement of the gears 72 and 86 with the racks 73 and 87 is maintained by the upright members 74 and 88.

From the floating roller 70, the tubular packaging structure with the marginal edges previously crimped and sealed, is carried over the idler roller 76, Figs. 4 and 1. This roller is mounted on shaft 77, the ends of which are journaled in frame 12. On the roller 76 are adjustably secured guide collar members 78 and 85. These members serve to keep the packaging material enclosure in proper alignment in feeding into succeeding rollers 79 and 82. As shown in Fig. 1, the roller 79 is mounted on a shaft 80 and is 75

5 maintained in compressive contact with roller 82 by spring pressed journal blocks 81. The lower roller 82, mounted on shaft 83, is preferably composed of a rubber material to afford frictional traction so that when the roller is rotated by hand wheel 84, the packaging strip from the floating roller 70 can be advanced through the rollers 78 and 82 into the end-crimping and cutting device. As shown in Figs. 2, 3 and 6, there are provided 10 crimping bar members 94 and 95, the opposing sides being serrated or fluted. These members form part of the manually operated mechanism to crimp and seal the ends of previously formed tubular packaging enclosure. The members 94 15 and 95 are hollow for accommodating heating cartridges 96 and 97, Figs. 2, 4 and 6, which have suitable electric terminal connections to supply current for heating purposes.

Referring to Fig. 6, the manually operated 20 mechanism also includes gripper block members 92 and 93 constructed of hard wood, or phenol condensation products. These gripper block members, manually operated, serve to hold the packaging enclosure strip 91 securely while the 25 end of the strip is being crimped and sealed and severed to a predetermined length. The gripper block members 92 and 93, as well as the crimping bar members 94 and 95 and the severing knife 98, are all inter-connected parts of a 30 mechanism, operated manually, which is supported by and functions freely within a frame work consisting of four upright members 151, 152, 153, and 154, bolted to a bed plate 127 on the general mounting frame 12. A cross bar member 155 35 is supported and bolted to these upright members. On top of the cross bar 155, there is provided U-shaped member 138, Fig. 6. To the flanges of the U-shaped member 138, two bar members 139 and 141, Figs. 2 and 3, extending 40 in opposite directions, are pivotally secured by pins 140 and 142. The offset ends of members 139 and 141 are provided with bolt members 143 and 145, Fig. 3, extending downward and connect by pin members 144 and 146, Fig. 2, with the 45 ends of the knife member 98. As shown in Figs. 2 and 6, there is provided a cross bar member 113 connected to the upper crimping bar 94. Between these two members there are provided layers 100 of heat insulating material, preferably 50 sheet asbestos. Between the lower crimping bar 95 and the bed plate 127, layers 101 are similarly provided.

To operate the crimping bar, gripper block and severing knife members described above, there is 55 provided a manually operated toggle mechanism consisting of four sets of members 102 to 109 inclusive, pivoted to thrust bar members, and operated through a suitable foot pedal.

Referring to Figs. 2 and 6, there are provided 60 pressure members 102 and 104, the upper ends of which are separated by a spacer washer 114 and pivoted to the extending ears 110 of a cross-bar member 134 by the pivot pin member 112. The lower ends of these pressure members 102 and 65 104 are separated by a spacer washer 113 and pivoted to thrust bar link members 171 and 172 by a pivot pin 117. There are also provided pressure members 103 and 105, the upper ends of which are likewise pivoted to link members 171 and 172 by 70 the pivot pin 117. The lower ends of these members 103 and 105 are pivoted to a bar member 113 by the pivot pin 114. The bar member 113 is secured by suitable screws with the crimping bar member 94. To prevent lateral displacement of the bar member 113 during its vertical motion,

there is provided at either end of the member, guiding rollers 162 and 163, respectively, which contact the uprights 152 and 154, thereby maintaining the crimping bar mechanism in a proper lateral position within the confines of the frame-work. As seen in Fig. 2, there is provided a cross-bar member 134 having a cylinder well provided with piston head 135. This piston head is secured to the cross bar member 155 by the threaded portion 136. Between the under side 10 of the piston head 135 and the bottom of the cylinder well, there is provided a compression spring 137. The cross-bar member 134 is provided with bolts 169 and 170 having a running fit through holes in the cross member 155. 15

Referring to Fig. 2, the upper ends of members 106 and 108 are separated by a spacer washer 175 and pivoted to the extending ears 111 of cross-bar member 134 by the pivot pin 118. The lower ends of pressure members 106 and 108 are pivoted to 20 the lever member 116, and link members 171 and 172 by the pivot pin 120. The upper ends of pressure members 107 and 109 are likewise pivoted to the lever bar 116 and link members 171 and 172 by the pivot pin 120 while the lower ends of 25 pressure members 107 and 109 are pivoted to the bar 113 by the pivot pin 119. The lever member 116, Fig. 2, is pivoted to an actuating lever member 158 by the pin 157. Lever member 158 is in turn pivotally supported by pin 159 held between 30 a pair of bosses 160 integral with the bed plate 127.

The lower end of this lever 158 is connected with a foot treadle 156, Fig. 1. When this foot treadle is depressed by the operator, the lever member 116 causes the pressure members 102— 35 109 to assume a vertical position, first forcing the gripper blocks 92 and 93, Fig. 6, into close contact, holding the package enclosure strip 91 securely, and then further exerting force on the upper heated crimping bar member 94, forcing it into a 40 close contact juxtaposition with the lower heated crimping bar member 95 to cause the crimping and sealing of a predetermined portion of the strip 91, then finally causing the knife 98 to move upwards to sever the overhanging portion of the 45 preformed packaging enclosure strip into a unit of predetermined length. The link member 171 has an extension 171a which contacts the upright 151 at the limit of movement of the toggle pressure members to a vertical position. 50

The foregoing operations in part are controlled through spring mechanisms illustrated in Figs. 2 and 6: In Fig. 2, there are provided two bar members 128 and 129 the ends of which are loosely mounted on pin members 125 and 126 which are 55 screwed into the bed plate 127. Between the ends of the upper and lower bar members 128 and 129, the pin members 125 and 126 are encircled by two short helical compression springs 121 and 123. Between the ends of bar member 129 and the bed 60 plate 127 are two longer springs 122 and 124 of less rigidity and similarly mounted on pins 125 and 126. On the opposite side of the pressure mechanism, as best seen in Figs. 4 and 6, two short springs 164 and 165 are mounted on pins 131 65 and 133, which are screwed to the bed plate 127. The upper ends of springs 164 and 165 contact with the under side of a plate 147, Fig. 6, and the lower ends contact with a plate 148, these plates being secured to the top side of the upper gripper block 92 and the bottom side of the lower gripper block 93, respectively. 70

The plate 147 is in contact with a cross bar member 166 mounted on pin members 114 and 119, Figs. 4 and 6. The opposite ends of pin 75

members 114 and 119 extend over the upper surface of the cross bar 128. The ends of plate 147, Fig. 4, are loosely fitted to the spring pin members 131 and 133, and bear upon the upper ends of springs 164 and 165; the vertical upward movement being limited by an adjusting nut 131a. The under side of gripper block 93, Fig. 6, has secured thereto a plate 148, the ends of which are loosely fitted over the spring pin members 131 and 133. There are also provided two longer springs 130, of greater rigidity than springs 164, 165, mounted respectively on rods 131 and 133. The springs extend between plate 148 and bed plate 127.

As seen in Fig. 6, a shelf member 167 is bolted to the bed plate 127 and is aligned with an extension table member 99 attached to the bed plate 127 by a bracket 168. On this extension table 99 which receives the severed package enclosure unit a movable clamp member 115 is provided. This member can be adjusted to regulate the length of the package unit as it is extracted through the crimping bars.

In the operation of the foregoing machine, the strips of packaging materials are fed from the reels, over the idler rollers and past the pin members which initially turn over the edges of the strips to form binding marginal edges. The consolidated strips then pass over the intermediate directing roller 23 which completes the turning of the edges. The strips of material then feed through the heated crimping rollers 31-34 which crimp and seal the turned over edges to form a continuous tubular shaped package enclosure structure. This tubular structure is then fed beneath the floating roller 70 which takes up the surplus slack in the strip that accumulates from the continuously operated edged crimping rollers when the subsequently manually operated mechanism is operated intermittently.

From the floating roller, the tubular package structure passes over idler roller 76 to pass between the manually operated rollers 79 and 82, Fig. 1. These rollers serve to effect the manual feeding of the preformed tubular packaging structure 91 through the space intermediate the gripper blocks 92 and 93, Fig. 6, into a position between the upper and lower crimping members 94 and 95, as controlled by the manually operated wheel 84. After the packaging structure 91 has been manually extended to a desired length, the manually operated gripping bars, crimping members and severing knife are actuated in sequence through force exerted on foot treadle 156.

The foot treadle 156 causes the connecting thrust bar 116 to move toward the right as seen in Fig. 2, thus causing the toggle members to straighten out and assume a perpendicular position. In assuming this perpendicular position, there are several separate and distinct operations performed. At the initial movement of the thrust bar 116, the lower ends of the members 102-109 exert a force through pins 114 and 119 to cause a downward movement of members 113, 128 and 166. This downward movement acts through the heavier springs 121 and 123 to depress the lighter spring members 122 and 124, Fig. 2, and at the same time depresses the spring members 164 and 165, Fig. 6. This latter action causes the gripping blocks 92 and 93 to close firmly gripping the packaging structure 91. In the same movement, the upper crimping bar member 94 is depressed to engage the structure 91. As the thrust bar member 116 continues its right hand movement, the toggle members exert an increasing force on the gripper block members

and the upper crimping bar, as well as the cross bar members 128 and 129, Fig. 6, further depressing the springs 122, 124, 130 and 132. The upper and lower crimping bar members 94 and 95 now come into close contact and crimp the end of the structure 91 under heat and pressure. In this step, the impact of the two crimping bar members is cushioned to a certain extent by the layers 100 and 101. When the crimping bar members are in contact, the bar member 129, 10 Figs. 2 and 6, is in contact with the shelf member 167 through the compression of the springs 124 and 122, thus offering resistance to any further downward movement caused by the action of the thrust bar 116 on the toggle members. As 15 the thrust bar member 116 continues its action on the toggle members 102-109 and the downward movement of bar 113 is arrested, the upper ends of the toggle members act to cause an upward movement of the cross-bar member 134, 20 Fig. 2. As this movement continues, the bolts 169 and 170, Fig. 2, secured to the member 134, come into contact and exert an upward pressure against the bars 139 and 141. The outer ends of these bars are connected with the ends 25 of the shearing knife 98. Thus it will be seen that the force of the bolts 169 and 170 acting upon the tension bar members 139 and 141 causes an upward movement in the knife connecting rods 143 and 145, raising the knife 98 30 adjacent the crimping bar 95, Figs. 2 and 6, to contact and sever the package structure 91. All of these progressive and successive operations of the manually controlled mechanism are effected through a single operation of a foot 35 treadle 156, Fig. 1.

Fig. 7 shows the packaging material strips as they are incorporated in the enclosure structure. In the particular embodiment here illustrated, the bottom or wider strip of material 1 has its 40 marginal areas folded over the top or narrower packaging strip 3. The color strips 5 and 7 are folded over the edges of the package structure and not only impart an ornamental appearance to the package structure, but serve to reinforce 45 the edges of the package structure. It will be understood, of course, that various changes and modifications of the arrangement and use of the packaging strips can be made without departing from the scope of the invention. This much of 50 the package structure constitutes the tubular formation which is fabricated on the automatic and continuously operated portion of the mechanism. As this preformed tubular structure is fed to the manually operated portion of the mechanism, selected lengths of the structure are transversely sealed at 161 along the areas "a" and 55 severed to form envelope structures. For example, in Fig. 7 the tubular structure is severed along the line Y-Y to form an open-end envelope as shown in Fig. 8. This envelope may be filled, as required, with a desired commodity.

In the operation of the equipment to form envelope structures, it will be noted that the transverse seal of one envelope is produced at the 60 time that the envelope formed by the previous transverse seal is severed. The structure of this form of package structure itself forms the subject matter of copending application Serial No. 47,549 filed October 31, 1935.

It will now be apparent that the foregoing machine provides for rapid fabrication of envelope structures by a combined form of automatic and manually controlled apparatus. Although a preferred form of machine has been disclosed, it 75

will be apparent that changes can be made therein without departing from the intended scope of my invention. I therefore do not desire to limit myself to the foregoing except as may be pointed out in the appended claims.

5 What I claim as new and original and desire to secure by United States Letters Patent is as follows:

1. A package forming machine comprising, 10 means for feeding plural layers of ribbon packaging material, roller means for crimping said layers upon both sides to close the edges thereof for forming a continuous tube-like packaging structure, a motor for continuously driving said 15 roller means, intermittent means for forming said tube-like structure into envelopes, said intermittent means comprising crimping and severing means for intermittently transversely crimping and severing said tube-like structure 20 in predetermined lengths, and feeding means for feeding said tube-like structure from said roller means to said intermittent means.

2. A machine in accordance with claim 1 in which said feeding means comprises, a take-up 25 arrangement accommodating an accumulation of said tube-like structure from said continuously operated roller means during the intermittent operation of said intermittent means.

3. A machine in accordance with claim 1 in which said roller means comprises a plurality of 30 axially aligned independently movable crimping rollers for operating on layers of said material of various selected widths.

4. A machine in accordance with claim 1 in which said intermittent means includes clamping 35 means for holding said tube-like structure stationary during severing and crimping operations, said means being effectively operable prior to said crimping and severing operations.

40 5. A machine in accordance with claim 1 in which said feeding means comprises an idler roller and pinions carried thereby, and racks with which said pinions mesh, said idler roller being adapted for free movement along said racks to hold taut 45 varying lengths of said tube-like structure accumulated due to the intermittent operation of said intermittent means.

6. A machine in accordance with claim 1 in which said roller means comprises a pair of shafts 50 intergeared with said motor, heater means within said shafts, and crimping elements carried on said shafts and axially adjustable thereon to accommodate various widths of said material.

7. A machine in accordance with claim 1 in which said intermittent means include clamping 55 means, crimping means, severing means, and unitary means for operating the foregoing in successive order to clamp said tube-like structure, transversely crimp the same and to transversely sever the same.

8. A machine in accordance with claim 1 in which said intermittent means includes a plurality of reciprocatively operated elements for 60 transversely operating on said tube-like structure, and means for sequentially operating said elements in predetermined order.

9. A machine in accordance with claim 1 in which said intermittent means comprises clamping 65 means, crimping means, severing means, and means for operating the foregoing in sequential order to clamp, crimp and sever said tube-like structure, and in which said feeding means comprises an arrangement for accommodating an accumulation of said tube-like structure from said 70 continuously driven roller means during the time

the movement of said tube-like structure is arrested by said clamping means.

10. A package forming machine comprising, 5 means for feeding plural layers of packaging material and means for joining said layers to form package structures comprising, clamping means for clamping said layers in a predetermined position, reciprocatively operating sealing means, severing means, and means for operating said clamping, sealing and severing means automatically in a predetermined sequence in the order mentioned.

11. A package forming machine comprising, a general mounting structure, means for feeding a plurality of super-imposed layers of packaging 15 material, a pair of shafts supported by said structure and carrying internal heating elements, crimping rollers carried on said shafts, means for guiding said layers of material between said rollers whereby said rollers heat and forcibly interdigitate the marginal edges of said layers to form a continuous tube-like structure, a motor driving means for continuously rotating said shafts to cause the continuous formation of said tube-like structure, a mechanically operable feeding means 25 comprising, a pair of complementary friction rollers through which said tube-like structure passes, equipment for operating on said tube-like structure fed through said last mentioned rollers, said equipment including reciprocatively operated 30 clamping means, reciprocatively operated sealing means, and severing means, manually operated actuating means for causing the sequential operation of the elements of said equipment to clamp, seal and sever selected lengths of said tube-like 35 structure in the order mentioned, and a take-up device positioned between said crimping rollers and said friction operated rollers, said take-up device being adapted to accommodate an accumulation of said tube-like structure from said 40 crimping rollers while the movement of said tube-like structure is arrested while being operated upon by said equipment.

12. A machine in accordance with claim 11 including a pivoted support for one of said shafts, 45 and a cam for moving said support to engage and disengage said clamping rollers to permit the threading therethrough of said layers of material.

13. A machine in accordance with claim 11 in which said equipment includes a reciprocative 50 guide structure, said clamping means including clamping blocks movably mounted in said structure for engagement with a complementary clamping block mounting stationary in said structure, said severing means comprising a knife element reciprocatively suspended in such structure, and said crimping means including a block member movably mounted in said structure for engagement with a complementary block member, 55 said actuating means comprising a mechanical movement for effectively sequentially imparting effective operating movement to said clamping block; said crimping block, and said knife element.

14. The machine in accordance with claim 11 65 in which said layers of material are of unequal width and including means for bending over the edges of both sides of the layer of greatest width to overlap the face of the layer of narrowest width before feeding through said crimping rollers.

15. A package forming machine comprising means for continuously feeding superimposed layers of packaging material while sealing together selected areas of said superimposed layers in a continuous process, equipment subject to 70 75

intermittent operation and arresting the movement of said sealed layers of material as fed from said last mentioned means, said equipment including means for further sealing said layers of material, and means intermediate said first mentioned means and said equipment for maintaining tension on said layers of material between said first mentioned means and said equipment while accommodating an accumulation of said material from said continuously operated first mentioned means during the interruption of the movement of said material through said equipment.

16. A package forming machine comprising, means for feeding opposed strips of thermo-plastically coated regenerated cellulose material, means for guiding said strips in contacting engagement with the marginal edges thereof turned over upon the surface of the strips, marginal crimping means for engaging said strips along opposite edges thereof in the turned-over areas, said crimping means being adapted to forcibly interdigitate said turned-over marginal areas with the normal surface of said layers of material by heat and pressure to produce a tubular formation, the heat acting to fuse said thermo-

plastic coating, and heat crimping means for transversely interdigitating said selected tubular structure at selected points, and means for severing said transversely interdigitated tubular structure at points adjacent said transverse interdigititation to produce, from said tubular structure, open mouthed bags having closed and double reinforced side walls, and closed bottoms.

17. The package forming machine in accordance with claim 16 in which said first-mentioned crimping means comprises mechanically complementary rollers positioned in pairs along opposite edges of said strips of material and provided with internal electrical heater elements.

18. A package forming machine comprising, means for feeding a plurality of super-imposed layers of packaging material, means for longitudinally sealing together said layers to form a continuous tube-like structure, other means for feeding and operating on said tube-like structure including reciprocatively operated sealing means and severing means, and mechanical means for conjointly operating said sealing and severing means to transversely seal and sever selected lengths of said tube-like structure.
